(57) **CLAIM**

The ornamental design for a plush panda bear, as shown and described.

DESCRIPTION

FIG. 1 is a front elevation view of a plush panda bear showing our new design;

FIG. 2 is a left side elevational view thereof;

FIG. 3 is a rear elevation view thereof;

FIG. 4 is a right side elevational view thereof;

FIG. 5 is a top plan view thereof; and,

FIG. 6 is a bottom plan view thereof.

The broken lines shown in the drawing are for illustrative purposes only and form no part of the claimed design.

The nose of the plush panda bear shown in the drawing is lined for the color red.
